DESIGN FOR A HANDBAG OR SIMILAR ARTICLE

Jack Passoff, Brooklyn, N. Y.

Application November 18, 1940, Serial No. 96,663

Term of patent 3½ years

To all whom it may concern:

Be it known that I, Jack Passoff, a citizen of the United States, residing at Brooklyn, in the county of Kings and State of New York, have invented a new, original, and ornamental Design for a Handbag or Similar Article, of which the following is a specification, reference being had to the accompanying drawing, forming part thereof, wherein—

Fig. 1 is a front view in perspective, of a handbag or similar article, showing my new design, and

Fig. 2 is a rear view in perspective thereof;

Fig. 3 is a front view in perspective, showing the lower compartment of the handbag or similar article, opened.

I claim:

The ornamental design for a handbag or similar article, substantially as shown.

JACK PASSOFF.
